(57) **CLAIM**

The ornamental design for a surgical tool with a needle provided with a slot, as shown and described.

DESCRIPTION

FIG. 1 is an overhead perspective view of a surgical tool with a needle provided with a slot.

FIG. 2 is a top plan view thereof.

FIG. 3 is a bottom plan view thereof.

FIG. 4 is a front side elevational view thereof, the back side elevational view is not provided as it is a mirror image of the front side elevational view.

FIG. 5 is a left elevational view thereof.

FIG. 6 is a right elevational view thereof.

FIG. 7 is an overhead perspective view of a distal portion of the needle provided with a slot.

FIG. 8 is a front side elevational view of a distal portion of the needle provided with a slot.

FIG. 9 is a top plan view of a distal portion of the needle provided with a slot; and,

FIG. 10 is a bottom plan view of a distal portion of the needle provided with a slot.

The broken lines represent unclaimed portions of the surgical tool with a needle provided with a slot and form no part of the claimed design.
